COIN BANK

Filed Jan. 31, 1923

2 Sheets-Sheet 2

UNITED STATES PATENT OFFICE

DAVID H. ZELL, OF BROOKLYN, NEW YORK

COIN BANK

Application filed January 31, 1928. Serial No. 250,853.

This invention relates to coin banks, and has for its primary object to provide a bank of simple and novel construction and a covering of flexible ornamental material for the walls thereof, the bank structure including a separable or removable wall and said wall carrying means to cooperate with means on the other bank walls to detachably secure said removable wall in its assembled position and also removably secure said ornamental covering in its applied position upon the bank walls. In this manner, when this covering becomes torn or soiled, it may be easily and quickly removed and replaced by a new cover.

More particularly, one of the novel features of my invention resides in the provision of a coin bank in the form of a miniature treasure chest having a body wall and separable end walls, and said end walls having ornamental plates provided with tongues, and the body wall at its opposite ends being provided with slots whereby said tongues may be inserted through the ornamental covering material on the body walls and through said slots and clinched upon the inner side of the body wall, thus simultaneously securing the covering material in place and also locking the ends in assembled relation with the body walls.

Another important feature of the invention resides in the provision of a removable bottom wall for the bank having an opening therein and a closure plate provided with a suitable lock to secure the plate in said opening, and said bottom wall and the side walls of the bank being provided with cooperating means concealed by the covering material on the bank walls to detachably secure the removable bottom wall in place.

With the above and other objects in view, the invention consists in the improved coin bank, and in the form, construction and relative arrangement of its several parts as will be hereinafter more fully described, illustrated in the accompanying drawings, and subsequently incorporated in the subjoined claims.

In the drawings, wherein I have illustrated one simple and practical embodiment of the

invention, and in which similar reference characters designate corresponding parts throughout the several views,—

Figure 1 is a side elevation illustrating one embodiment of my new coin bank;

Fig. 2 is a plan view thereof;

Fig. 3 is an end elevation;

Fig. 4 is a transverse section view taken on the line 4—4 of Fig. 1;

Fig. 5 is a longitudinal sectional view taken substantially on the line 5—5 of Fig. 3;

Fig. 6 is a detail perspective view of the removable bottom wall of the bank, and

Fig. 7 is a bottom plan view, the bottom wall being removed.

Referring in detail to the drawings, as herein shown, the bank is in the form of a miniature treasure chest having spaced parallel side walls 5 and a transversely curved top wall 6 which may be conveniently produced from a single metal sheet of suitable gauge or thickness.

The end walls 7 are preferably separable from the side and top walls of the bank, each of said end walls consisting of a properly cut or shaped sheet metal plate. The outer surfaces of the side and top walls of the bank are adapted to be covered with a thin sheet of flexible material indicated at 8, such as imitation leather or the like which may be suitably embossed or otherwise ornamented, the longitudinal edges of the side portions of this sheet of covering material being turned inwardly and upwardly around the edges of the side walls 5 of the bank as indicated at 9.

A similar ornamental material shown at 10 also covers the outer face of each of the end walls 7 and is held thereon by an ornamental end plate 11 extending over the outer surface of said ornamental material 10. This plate is provided with laterally projecting marginal flanges 12 to extend inwardly upon the ends of the side and top walls of the bank, and the edge of this flange is provided with a plurality of spaced bendable tongues 13. The opposite end of each flange 12 is also provided with a bendable tongue or extension 14. Between the ends of the flange, the lower edge of the plate is bent

inwardly and upwardly upon the inner side of the end wall 7 of the bank as shown at 15.

As herein shown, the tongues 13 are provided only upon the transversely extending part of the flange 12, but it will of course, be understood that if desired similar tongues 5 may also be provided upon the vertical portions of this flange. At corresponding points, the top wall of the bank adjacent each 10 of its ends is provided with suitable slots 16.

From the above description, it will be understood that the end walls 7 having been assembled with the covering sheets 10 and the outer ornamental plates 11, after the 15 covering material 8 is applied upon the top and side walls of the bank, the end walls 7 are arranged in place, and the tongues 13 on the flanges 12 carried by these end walls are forced through the flexible covering material 8 and through the slots 16 and are clinched downwardly upon the inner surface of the top wall 6 of the bank as clearly shown in Figs. 5 and 7 of the drawings. The tongues 14 at the ends of the flanges 12

25 are then bent inwardly upon the edges 9 of the covering material which is engaged against the inner faces of the side walls 5 of the bank at their lower edges. Thus, it will be apparent that the covering material 8 is smoothly and securely held in its applied position upon the surfaces of the bank walls and the end walls 7 are also rigidly fixed in their assembled positions relative to the side and top walls of the bank.

35 One of the end walls 7 and the ornamental plate 11 have a coin inserting slot 17 cut therethrough while a circular opening 18 is provided in the other end wall and plate 11 through which a rolled bill may be inserted.

40 The bottom of this chest shaped bank is closed by the removable bottom wall 19 shown in detail in Fig. 6 of the drawings. This wall is provided with the marginal flanges 20 and 21 extending along the side and end edges respectively, thereof which are adapted to fit snugly between the side and end walls 5 and 7 of the bank and frictionally engage the inwardly and upwardly 45 turned edges 9 of the covering material on the bank walls. The side flanges 20 in spaced relation to their opposite ends are provided with suitably formed openings 22 and in the same relation to the end walls 7 of the bank, the side walls 5 thereof are provided 55 with the inwardly struck resiliently yieldable tongues 23, each of which is provided with a locking nut 24 projecting outwardly therefrom and adapted for engagement 60 through one of the openings 22. It will thus be understood that when the removable bottom wall 19 is applied, the flanges 20 thereof extend between the tongues 23 and the side walls 5 of the bank, spring the tongues inwardly until the openings 22 are in line with

the studs 24 when the latter will snap into said openings, thus detachably locking the bottom wall in place. Since the ornamental covering sheet 8 on the bank walls extends over the openings formed by the inwardly struck tongues 23, this locking or securing means for the removable bottom wall is concealed so that no clew is afforded as to the manner in which this bottom wall might be detached and removed and access thereby obtained to the contents of the bank. 70

The bottom wall 19 is provided with an opening 25 therein, preferably, though not necessarily of rectangular form, and said wall along each edge of the opening 25 is formed with an inwardly projecting angularly offset flange 26. This opening is adapted to be closed by means of the plate 27 which carries a suitable form of key operated lock 28 having a movable part adapted to coact with the side flanges 26 and thereby lock said plate in the opening 25 so that the coins may not be removed from the bank except by the possessor of the proper key. 80

From the above description, it will be understood that should the covering material 8 on the bank walls at any time become badly worn or soiled, the bank may be returned to the manufacturer and provided with a new ornamental covering sheet at trifling cost in comparison with the cost of an entirely new bank. Thus the old cover can be readily removed by simply first forcing the tongues 23 95

inwardly so as to permit the removal of the bottom wall 19, and then bending the tongues 13 and 14 so that they can be disengaged from the top and sides of the bank, thus permitting of the removal of the end walls 7, thereby entirely freeing the secured edges of the covering material 8 so that it may be re-100

moved. After the new covering material has been applied on the side and top walls of the bank, the end and bottom walls are then re-assembled in the manner above explained and in such reassemblage of the bank walls, the covering material is simultaneously securely fixed and held in its applied position. Thus, it will be understood that I have provided a coin collection bank of this character such as is generally used by banking 110

institutions and distributed to small depositors, the initial manufacturing cost of which is relatively small and which may be also indefinitely maintained in an ornamental and attractive condition, at very small additional expense. I have herein referred to this coin bank as simulating a treasure chest, but it will be understood that the bank may also be produced in many other fanciful forms or shapes. Also I have specifically 120

described a particular means for detachably securing the end and bottom walls of the bank in assembled relation with the side and top walls substituted for these mechanical details. Accordingly, in the practical de- 125

velopment of the invention as herein disclosed, I do not desire to be limited to these detail features, but reserve the privilege of resorting to all such legitimate changes therein as may be fairly embodied within the spirit and scope of the invention as claimed.

I claim:

1. A coin bank having top, bottom and side walls, and end walls separable from said top, bottom and side walls, in combination with an ornamental flexible covering material for the top and side walls, means carried by each end wall for removably securing the same in assembled relation with the top and side walls, one of the latter walls having slots therein, and said means including bendable tongues adapted to pierce the covering material and extend inwardly through said slots to thereby detachably secure said covering material in place.

2. A coin bank having top and side walls, and separable end and bottom walls, in combination with ornamental flexible covering material for the top and side walls of the bank, and said end and bottom walls having means engaging the edges of the covering material to detachably secure the same in place and also having means to coat with complementary means on the top and side walls of the bank and thereby removably secure said end and bottom walls in their assembled positions.

3. A coin bank having relatively fixed body walls and a separable wall, an ornamental covering material for said body walls, said body walls and the separable wall having a plurality of cooperating yieldable tongues and openings, and said tongues piercing the covering material and extending through said openings to removably secure said separable wall and the covering material in assembled position with respect to the body walls of the bank.

4. A receptacle comprising a sheet metal body structure, an ornamental flexible covering material superimposed upon the walls of the body structure, and means for securing said covering material in impermanently attached relation to the body walls consisting of external ornamental sheet metal members having parts overlying the edges of said covering material and detachably clinched thereon to separably retain said members in assembled relation with the body walls and detachably secure the covering material upon the latter.

In testimony that I claim the foregoing as my invention, I have signed my name hereto.

DAVID H. ZELL.
